UNITED STATES PATENT OFFICE.

ELMER ELSWORTH HANNA, OF CHICAGO, ILLINOIS.

FLUID-PRESSURE RIVETING-MACHINE.

No. 823,274.

Specification of Letters Patent.

Patented June 12, 1906.

Application filed May 15, 1903. Renewed April 26, 1906. Serial No. 318,680.

To all whom it may concern:

Be it known that I, ELMER ELSWORTH HANNA, a citizen of the United States, residing at Chicago, in the county of Cook and State of Illinois, have invented certain new and useful Improvements in Fluid-Pressure Riveting-Machines, of which the following is a specification.

The principal object of this invention is to provide a fluid-pressure riveting-machine with a system of compound levers for transmitting power and motion from the prime mover to the riveting-dies, quickly at first, with gradually-reduced speed and increasing pressure, and during the final riveting operation at a continued substantially uniform speed and pressure, as will more fully hereinafter appear.

The invention comprehends principally a fluid-pressure riveter in which there are combined a plunger bearing a riveting or similar tool, a main operating-lever, link mechanism pivotally connecting the main operating-lever and plunger together, and other links connecting main operating-levers with frame, a fluid-pressure cylinder, a reciprocating piston therein provided with a projecting piston-rod, and an intermediate lever pivotally secured on the frame of the machine and pivotally connecting the piston-rod and main operating-lever together.

While the invention is designed primarily for what is termed "fluid-pressure" riveters, manifestly the same can be employed with other types of rivets.

The invention consists, further and finally, in the features, combinations, and details of construction hereinafter described and claimed.

In the accompanying drawings, Figure 1 is a side elevation showing the cylinder mechanism and section of a fluid-pressure riveter as it appears when constructed in accordance with these improvements; Fig. 2, a plan view of the same looking at it from above; Fig. 3, an enlarged front elevation of the upper arm and supporting mechanism of the riveter as it appears in Fig. 1; Fig. 4, a side elevation of the same, partly in section, taken on line 4 of Fig. 3 looking in the direction of the arrow; and Fig. 5, a diagram of the amount of motion transmitted by the system of levers to the plunger mechanism.

In the art to which this invention relates, it is well known that it has long been desired to provide a fluid-pressure riveter with positive

mechanical elements, such as a system of levers interposed between the prime mover and the riveting-tool in such a manner as to obtain a substantially rapid movement with gradually-reduced speed and increasing pressure at first and then a continued substantially uniform transmission of power and motion at the end or during the time the final work is being performed. To this end this invention is principally designed.

In constructing a fluid-pressure riveter in accordance with these improvements I make a main bifurcated frame portion *a* substantially C-shaped in contour when looked at in side elevation, as shown in Fig. 1. Slidably mounted in the upper arm *b* of this bifurcated frame is a plunger *c*, bearing a riveting or other operating tool *d*, the shank of which is screw-threaded therein, so that it may be adjusted or removed for purposes of replacement by a similar or other tool, as occasion requires. To operate this plunger with its riveting-tool, a main operating-lever *e* is provided, fulcrumed within the machine and at right angles with the line of motion of said plunger. A pair of links *f* is provided and pivotally secured within the frame of the machine at *g*, in which by means of trunnions *h* the main operating-lever is fulcrumed. Examining particularly Fig. 4, it will be seen that the short portion of the main operating-lever extends forward of the fulcruming-trunnions and the main portion to the rear, also that the front portion is hollowed out to receive the link *i*, that is pivotally secured therein and also pivotally secured to the plunger, so that power and motion may be transmitted from said main operating-lever, vastly multiplied, to the plunger mechanism. To operate said main operating-lever, a fluid-pressure cylinder *j* is provided and pivotally secured at *k* to a rearward extension *l* on the portable frame of the machine. This cylinder is provided with a reciprocating piston *m*, and a piston-rod *n* projects upwardly and outwardly therefrom. An intermediate lever *p* is provided, fulcrumed in an extension of the machine at *q*, which pivotally connects the main operating-lever and the piston-rod together.

By the foregoing arrangement of levers it will be seen that the desired transmission of power and motion is secured. As shown in Fig. 5, the first inch of movement of the main piston obtains substantially twice the length of movement of the plunger, due to the fact

that the members of the toggle mechanism *f* and *i* are in their position of greatest angle to the line of movement of plunger *C*. The second inch of movement produces about an 5 inch of plunger motion, and each succeeding movement of plunger becomes less in proportion to piston movement until toggle members *f* and *i* reach positions where their center lines are approximately parallel with line 10 of motion of plunger *C*, where movement due to toggling action practically stops, while the last six inches of motion of said main piston obtains a continued substantially uniform movement, greatly reduced for every inch 15 thereof, due solely to the action of main lever *c*, oscillating on fulcrum *h*, as shown in the graduations within the main lines, (indicated by 6" in said figure,) all of which will be understood and appreciated by those skilled in 20 the art. In the toggle-lever type of riveters heretofore employed when parts having varying or unequal thickness were to be riveted together or when its rivets were of varying length the rivet set in each instance required 25 adjustment, so that the required pressure could be secured at the proper interval or during the active riveting interval. It is the necessity of this setting or repeated adjustment of the rivet set that this invention is 30 designed to avoid. By the arrangement of levers above described the substantially maximum or necessary active riveting or working pressure is continuous for a considerable distance, so that were the parts being riveted 35 warped or of unequal thickness at one point the pressure would be sufficient to complete the riveting at that point, while were the plates or parts reduced in thickness the continuous maximum pressure would, as in 40 the other case, complete the riveting, and so without adjustment. Briefly, the distance of travel of the rivet set during the active or maximum pressure interval is sufficient to compensate for inequalities in the material 45 being riveted and renders the machine useful without subsequent adjustment for riveting different thicknesses of material. Again, by the gradual increasing pressure and decreasing speed the relative lower pressure can be 50 employed or utilized to primarily upset the end of the rivet, while the continuous maximum pressure finally closes the heads onto the plates, forcing the plates together, and completes the final union of the parts.

55 In the art of riveting it is well known that it is usual to have the main supporting-frame of the machine remain relatively stationary and that the plunger has the actual reciprocating motion, so that the "headed" portion 60 of the rivet, is usually placed down upon the anvil *t* and the upper end of the rivet upset. This is quite objectionable in some kinds of work, in that only one rivet can be set in position at a time, and considerable care has to 65 be exercised to prevent it from falling out.

In my improved arrangement any number of rivets may be set in position, as desired, with the headed portion up and the unfinished portion projecting down through the work. It is necessary, however, in order to operate upon rivets thus arranged without inverting the riveting-machine, that the machine or supporting-frame should have movement while the plunger remains stationary. In other words, the upper portion remains stationary, while 70 the lower, usually the anvil, moves and performs the heading operation. To facilitate these operations, the plunger is provided with projecting pins or studs *u*, passed through elongated openings *w* in the frame of the machine. Secured to these projecting pins or studs on each side of the machine is a pair of bars or links *s*, which are also pivotally secured to the frame of the machine by means of links *r* and the intermediate lever *p*. A 80 pair of chains *x* may be used for hanging said bars, and thereby the riveter, in position.

In operation when the plunger is reciprocating, relatively speaking, and contacting the rivet during the heading process the main 90 portion of the machine with its anvil is forced upwardly, and when the reciprocating plunger is, relatively speaking, moved upward the main supporting-frame of the machine is permitted to drop to its normal position, thus 95 enabling the operator to insert any number of rivets in advance of the actual riveting process, all of which will be understood and appreciated by those skilled in the art.

I claim—

1. In a fluid-pressure riveter, the combination of a frame, a plunger bearing a riveting or similar tool, a main operating-lever, a swinging fulcrum for such lever, link mechanism connecting the main operating-lever and plunger together, a fluid-pressure cylinder, a reciprocating piston therein provided with a piston-rod projecting therefrom, and an intermediate lever pivotally mounted upon and secured to the frame of the machine and pivotally connected with the piston-rod and main operating-lever, substantially as described.

2. In a fluid-pressure riveter, the combination of a supporting-frame, a plunger reciprocatingly mounted therein and carrying a riveting or similar tool, a main operating-lever, link mechanism pivotally mounted in the frame of the machine and in which the main operating-lever is fulcrumed, link mechanism connecting the plunger and main operating-lever together, a fluid-pressure cylinder, a reciprocating piston mounted therein and provided with a piston-rod projecting therefrom, and intermediate lever mechanism fulcrumed in the frame of the machine and pivotally connecting the main operating-lever and piston-rod together, substantially as described.

3. In a fluid-pressure riveter, the combi-

5. In a portable frame, a plunger slid-
ingly mounted therein and provided with a
riveting or similar tool, a main operating-
lever, a swinging fulcrum for the said main
lever, link mechanism pivotally connecting
the plunger and main operating-lever to-
gether, a fluid-pressure cylinder pivotally
secured on the portable frame of the ma-
chine, a reciprocating piston mounted there-
in and provided with a piston-rod projecting
therefrom, and an intermediate lever ful-
crumed in the frame of the machine and piv-
otally connecting the main operating-lever
and piston-rod together, substantially as de-
scribed.
15. 4. In a fluid-pressure riveter, the combi-
nation of a bifurcated supporting-frame, a
plunger slidably mounted in one arm of said
frame and provided with a riveting or simi-
lar tool, pin mechanism secured to such
plunger and extending out through openings
in the frame of the machine, an operating-
lever fulcrumed in the frame of the machine,
link mechanism pivotally connected with the
plunger and with the operating-lever, a fluid-
pressure cylinder provided with a recipro-
cating piston and piston-rod connected with
the operating-lever, and hanging mechanism
connected with the pins on the plunger, sub-
stantially as described.
25. 5. In a fluid-pressure riveter, the combi-
nation of a portable bifurcated frame, a
plunger slidably mounted in one arm of said
frame and provided with a riveting or simi-
lar tool, pin mechanism secured to such
plunger and extending out through elongated
openings in the frame of the machine, a fluid-pressure cylinder provided with a re-
ciprocating piston and piston-rod, a system
40 of compound levers for transmitting power
and motion from the piston-rod to the slid-
ing plunger, and link mechanism pivotally
secured to the projecting pins on the plunger
and connected with said system of levers by
45 which the machine is hung in position and the
riveting operations facilitated, substantially
as described.
6. In a fluid-pressure riveter, the combi-
nation of a bifurcated frame portion, a plun-
ger slidably mounted in one arm of such
frame and provided with a riveting or simi-
lar tool, a main operating-lever fulcrumed at
right angles with the line of motion of said
plunger, link mechanism pivotally mounted
55 in the frame of the machine upon which said
main operating-lever is fulcrumed, link
mechanism connected with the plunger and
main operating-lever, a fluid-pressure cylin-
der secured to the frame of the machine, a
60 reciprocating piston mounted therein and
provided with a projecting piston-rod, and
an intermediate lever fulcrumed in the frame
of the machine and pivotally connecting the
main operating-lever and piston-rod to-
gether, substantially as described.
7. In a fluid-pressure riveter, the combi-
nation of a C-shaped portable supporting-
frame, a plunger slidably mounted in one
arm of said frame and provided with a rivet-
ing or similar tool, projecting pin or stud
mechanism secured to said plunger, a main
operating-lever fulcrumed at right angles
70 with the line of motion of said plunger, link
mechanism pivotally secured in the frame
of the machine in which such main operating-
lever is fulcrumed, link mechanism pivotally
securing the plunger and main operating-
lever together, a fluid-pressure cylinder
75 pivotally secured to the frame of the ma-
chine, a reciprocating piston mounted there-
in and provided with a piston-rod projecting
therefrom, an intermediate lever fulcrumed
in the frame of the machine and pivotally
securing the main operating-lever and pis-
ton-rod together, and hanging-levers pivot-
ally connected with the lever mechanism of
the machine and with the projecting pins on
the plunger mechanism, substantially as de-
scribed.
8. In a machine of the class described, the
combination of a frame, a plunger mounted
in such frame and movable with relation
thereto, and means for moving such plunger
with relation to the frame at a relatively
rapid and gradually-decreasing speed with
increasing pressure throughout the first por-
tion of its stroke and at a relatively slow uni-
form speed and pressure throughout a sub-
sequent portion of the stroke, substantially as
described.
9. In a machine of the class described, the
combination of a frame, a plunger mounted
in such frame and movable with relation
thereto, means for applying a relatively light
pressure and relative rapid gradually-de-
creasing speed to such plunger throughout a
portion of its stroke and a maximum uni-
form pressure and substantially uniform speed
throughout the last portion of its stroke, sub-
stantially as described.
10. In a machine of the class described,
the combination of a frame, a plunger mount-
ed in such frame movable with relation
thereto, a fluid-pressure cylinder, a piston
movably mounted in such cylinder, means
for admitting fluid under pressure to the cyl-
inder-chamber, and means for connecting
such piston and plunger, whereby a rela-
tively gradually-decreasing speed and a
gradually-increasing pressure is transmitted
from the piston to the plunger throughout a
portion of the stroke of the plunger and con-
tinued substantially uniform speed and a
maximum substantially uniform pressure
throughout the last portion of its stroke, sub-
stantially as described.
11. In a machine of the class described,
the combination of a frame, a plunger mount-
ed in such frame movable with relation
thereto, a fluid-pressure cylinder, a piston
130

movably mounted in such cylinder, means for admitting fluid under pressure to the cylinder-chamber, lever mechanism connecting such piston and plunger adapted to transmit an increasing pressure to the plunger and a relatively rapid gradually-decreasing speed throughout a portion of its stroke and a maximum substantially uniform pressure and speed throughout a substantial subsequent portion of such stroke, substantially as described.

12. In a machine of the class described, the combination of a frame, a piston-cylinder, a piston movably mounted in such piston-cylinder, means for admitting fluid under pressure to such piston-cylinder, a plunger mounted in such frame, and connected mechanism between the plunger and piston whereby the plunger is moved at a gradually-decreasing speed with relation to the movement of the piston during the first portion of its stroke and at a slower substantially uniform speed and in substantially uniform relation to the movement of the piston during a subsequent portion of its stroke, substantially as described.

13. In a machine of the class described, the combination of a frame, a piston-cylinder mounted thereon, a piston movably mounted in such piston-cylinder; means for admitting fluid under pressure to such piston-cylinder, a plunger mounted in such frame movable at a gradually-decreasing speed and increasing pressure with relation to the movement of the piston during the first portion of its stroke and at a substantially uniform speed and pressure and in substantially uniform relation to the movement of the piston during the last portion of its stroke, and lever mechanism connecting such plunger and piston for operating the plunger in such relation to the piston, substantially as described.

14. In a machine of the class described,

the combination of a frame, a piston-cylinder mounted thereon, a piston movably mounted in such piston-cylinder, means for admitting fluid under pressure to such piston-cylinder, a plunger mounted in such frame movable at a gradually-decreasing speed with relation to the movement of the piston during the first portion of its stroke and at a substantially uniform speed and in substantially uniform relation to the movement of the piston during the last portion of its stroke, a riveting-tool mounted in such plunger, an anvil mounted in the frame opposite such riveting-tool, and lever mechanism connected with such plunger and operated by such piston for transmitting an increasing pressure and relatively rapid decreasing speed to the plunger during the first portion of its stroke and a substantially uniform maximum pressure and speed throughout the last portion of its stroke, substantially as described.

15. In a machine of the class described, the combination of a movable frame having upper and lower arms for receiving material to be operated upon therebetween, a plunger mounted in such movable frame and provided with a riveting-tool, means for holding such plunger in substantially fixed position, a lower riveting-tool mounted in the lower arm movable therewith and with relation to the plunger and the material to be operated upon, and means for moving the frame and such lower riveting-tool upward and downward with relation to the plunger under gradually-increasing pressure throughout the first portion of its stroke and under maximum and substantially uniform pressure throughout the last portion of its stroke, substantially as described.
